UNITED STATES PATENT OFFICE

93,166

DESIGN FOR LACE FABRIC OR THE LIKE

John Hufenus, West New York, N. J.

Application July 14, 1934, Serial No. 52,584

Term of patent 3½ years

To all whom it may concern:

Be it known that I, JOHN HUFENUS, a citizen of the United States, residing in West New York, county of Hudson, State of New Jersey, have invented a new, original, and ornamental Design for a Lace Fabric or the like, of which the following is a specification reference being had to the accompanying drawing, forming a part thereof.

The figure is a plan view of a lace fabric or the like, showing my new design.

The cross-hatching appearing on the drawing represents the background of the fabric.

I claim:

The ornamental design for a lace fabric or the like, as shown and described.

In testimony whereof I have signed this specification.

JOHN HUFENUS.
